PORTABLE HEATER

William L. Lamkin, Porterville, Calif.

Application July 15, 1937, Serial No. 153,855

1 Claim. (Cl. 44—38)

This invention relates to an improved portable heater for use in protecting orchards, vineyards, gardens and trees from damage by frost.

At present heaters employed to protect orchards from damage by frost have consisted of metallic receptacles for holding the combustible material to be burned and are objectionable because of the large number which must be used to protect an orchard of large acreage and the cost of the labor which must necessarily be employed to maintain the receptacles in proper working condition.

It is an object of the present invention to provide a heater which is constructed wholly of a combustible material pressed or molded into a shape which will insure its ready burning for a pre-determined time, thus eliminating the need of using metal containers.

Other objects and advantages of the invention will be apparent during the course of the following description.

In the accompanying drawing, forming a part of this specification and in which like numerals are employed to designate like parts throughout the same—

Fig. 1 is a top plan view of the heater,
Fig. 2 is a vertical sectional view of the same,
Fig. 3 is a side elevation of the heater,
Fig. 4 is a bottom plan view of the same,
Fig. 5 is a perspective view of the heater with the cover removed, and,

Fig. 6 is a perspective view of a slightly different form of heater with the cover partly in section.

In the drawing, wherein for the purpose of illustration, I have shown a preferred embodiment of my invention, the numeral 20 denotes the body of the heater which is wholly constructed of combustible material such as coal dust and a suitable binder or other materials employed in the manufacture of briquettes. The combustible material is pressed or molded to form a body of square or circular shape in cross section having a frusto-conical chamber or recess 24 arranged centrally and longitudinally of the body and the walls of the chamber have a series of vents 21 extending transversely therethrough. The bottom of the chamber 24 is provided with a central draft opening 23 which communicates with the channel 22 extending across the bottom of the body which permits air to enter the bottom of the

chamber when the body is standing on its end. A metal cover 10 is provided for the top of the body having a depending marginal flange which engages over the sides of the body. In Fig. 5 the square type of heater is shown, while in Fig. 6 the circular type is shown, the body 26 of the circular type being of the same construction as the square type except for its outer configuration. A modified type of cover 11 is shown in Fig. 6 which includes the provision of transverse ribs 12 arranged in crossed relation beneath the cover and connected to the depending flange of the cover. The ribs 12 serve to support the cover on the upper edge of the body in raised relation thereto to allow for a draft beneath the cover. 15

In use, the chamber 24 of the heaters is filled with kindling of a type which will produce an intense heat to readily ignite the body of the heater which will burn until the entire body has been consumed. To prolong the burning of the 20 heater briquettes may be placed in the chamber 24, or the size of the heater may be increased. The opening 23 in the bottom of the chamber and the vents 21 in the walls of the chamber provide sufficient draft to insure burning of the 25 entire heater and the metal cover protects the heater from rain. Thus, it is seen I have provided a heater which is inexpensive to construct and which is entirely consumed by burning, eliminating the necessity of maintaining receptacles. 30

It is to be understood that the form of my invention herein shown and described is to be taken as a preferred example of the same and that certain changes in the shape, size and arrangement of the parts may be made without departing from the spirit of the invention or the scope of the subjoined claim. 35

Having thus described my invention, I claim:

A heater of the type described comprising an 40 elongated upright body of molded combustible material, said body having a central longitudinal chamber of inverted frusto-conical shape open at the top, adapted to receive kindling, the side 45 walls of said body having a series of vents therethrough communicating with the chamber and the bottom wall having a central vent extending therethrough, and a channel extending across the bottom of said body open at its ends and intersecting the vent in the bottom wall. 50

WILLIAM L. LAMKIN.
